FLUID OPERATED SWITCH

Morris Katcher, New York, N. Y.

Application July 23, 1937, Serial No. 155,161

6 Claims. (Cl. 200—83)

This invention relates to fluid operated switches and more particularly to switches of this character adapted for installation in fluid pressure brake systems for motor vehicles, for completing a circuit to a stop light when the brakes are applied.

Objects of the invention are to simplify and improve the construction and operation of switches of this character, to render them inexpensive to manufacture, convenient to install and not likely to get out of order.

Other objects and advantages will become apparent upon a further study of the description and drawing, in which:

15 Fig. 1 is a section through the switch with the diaphragm and contact spring in normal position.

Fig. 2 is a section through the switch with the diaphragm and contact spring shown flexed as 20 when fluid pressure is applied.

Fig. 3 is a top plan view of Fig. 1.

Fig. 4 is a top plan view of the contact spring shown by itself, and

25 Fig. 5 is a section taken along the line 5—5 of Fig. 4.

The switch comprises a block or body member 6 of an insulating material such as a phenol condensation product. Member 6 is set in a cup-like casing having a base portion 8 and an annular 30 flange or wall portion 7. A central boss 9 is provided for the base portion 8 and is threaded for connection into a fluid pressure system such as a hydraulic brake system. A passage 10 is provided in boss 9 so that the pressure of a pressure 35 system may be applied to the interior of the casing.

Body member 6 has embedded therein a pair of spaced terminals 11 and 12. These terminals are drilled and tapped to receive screws 13 and 40 thus afford convenient connection for leads 14 of a stop light or other alarm circuit. The lower ends of terminals 11 and 12 are exposed through the bottom surface of body member 6. The bottom of terminal 12 extends farther below said 45 surface than the bottom of terminal 11.

Between body member 6 and base portion 8 is pinched at its edges, a rubber diaphragm 15, with a fish paper washer 16 on top of it. Body member 6 is held tight down upon base portion 8, by 50 lip 17 which is pressed over from wall portion 7. The inner surface of block 6 has its central portion at a higher elevation than its marginal portion.

A plate spring, denoted in its entirely by 55 numeral 18, has a substantially semi-cylindrical

raised portion 19 with an opening 20 in its top. Terminal 11 has its lower end inserted through opening 20, and its edges peened over to grip the underside of portion 19, a metal washer 21 being inserted between. Flanges 22 are turned up at diametrically opposite edges of spring 18 to act as spacers for holding down said edges of the spring when the switch is assembled. Pressure upward against the spring causes flanges 22 to react against the bottom of body member 6. 10

Normally, with no fluid pressure applied to the underside of diaphragm 15, spring 18 is away from the bottom of terminal 12. However, when fluid pressure is transmitted through passage 10 against the underside of diaphragm 15, the latter 15 presses up upon spring 18, bowing the latter up against the bottom of terminal 12. Spring 18, being fixed to terminal 11, the application of fluid pressure to the underside of diaphragm 15, 20 closes the circuit between terminals 11 and 12. 20

The terms used in the claims relating to position such as "base", "top", "upper", etc., are intended to be relative only.

I claim:

1. A fluid operated switch comprising a casing 25 having a chamber formed therein, the bottom portion of the casing having a passage through it leading into said chamber, a flexible diaphragm in said chamber extending across and sealing said passage, a pair of spaced terminals insulatively mounted in the upper portion of the casing having their inner ends exposed to the interior of the casing, and a metallic plate spring in the chamber above said diaphragm having a raised portion at one end in contact with the first of said terminals while the opposite end of the spring is normally out of contact with the second of said terminals, the opposite sides of the spring intermediate said ends being held down at all times by portions of the casing against substantial 30 motion towards said second terminal, said diaphragm bowing up the spring between said sides against said second terminal when pressure is sent through said passage. 35

2. A fluid operated switch comprising a casing 45 having a chamber formed therein, the bottom portion of the casing having a passage through it leading into said chamber, a flexible diaphragm in said chamber extending across and sealing said passage, a pair of spaced terminals insulatively mounted in the upper portion of the casing having their inner ends exposed to the interior of the casing, and a metallic plate spring, in the chamber above said diaphragm, having a raised portion at its end below the first of said terminals, 50

55

the opposite end of the spring being normally a substantial distance below the second of said terminals, the sides of the spring, intermediate said ends being bent upward for reacting against 5 portions of the casing for holding down said spring at said sides, said diaphragm bowing up the spring between its held down sides against said second terminal when pressure is sent through said passage, said spring thereby closing 10 the circuit between the terminals.

3. A fluid operated switch comprising a casing having a chamber formed therein, the bottom portion of the casing having a passage through it leading into said chamber, a flexible diaphragm in said chamber extending across and sealing said passage, a pair of spaced terminals insulatively mounted in the upper portion of the casing having their inner ends exposed to the interior of the chamber, and a metallic plate 15 spring in the chamber above the diaphragm having a raised semi-cylindrical portion at its end below the first of said terminals, the top of said semi-cylindrical portion being fastened to said first terminal, the opposite end of said spring 20 being normally at a distance from the second of said terminals, opposite sides of the spring, intermediate said ends, being held down at all times by portions of the casing against substantial motion upward, said diaphragm bowing 25 up the spring between said held down sides, causing, thereby, the spring to contact said second terminal when pressure is sent through said passage.

4. A fluid operated switch comprising a casing with a cover portion, said casing having a chamber formed therein closed by said cover portion, the bottom portion of the casing having a passage through it leading into said chamber, a flexible diaphragm in said chamber extending 30 across and sealing said passage, a pair of spaced terminals insulatively mounted in the upper portion of the casing having their inner ends projecting into said chamber, the first of said terminals projecting into said chamber a substantially greater distance than the second, and a metallic plate spring, in the chamber above said diaphragm, having a raised portion at one end occupying substantially the central portion thereof, said end being fixed to the second of 35 said terminals, the opposite end of the spring

being normally at a distance below said first terminal, the sides of the spring intermediate said ends being bent upward engaging the underside of the cover portion holding said spring down adjacent said sides, said diaphragm bowing up the spring between said sides against said first terminal when pressure is sent through said passage. 5

5. A fluid pressure operated switch comprising a casing having a chamber formed therein, the bottom portion of the casing having a passage through it leading into said chamber, a flexible diaphragm in said chamber extending across and sealing said passage, a pair of spaced terminals insulatively mounted in the upper portion 10 of the casing having their inner ends exposed to the interior of the chamber, and a metallic spring substantially in the form of a disc having one end engaging the first of said terminals, the opposite end of the disc being normally at a distance below the second terminal, the sides of the disc intermediate said ends being bent upward, the bent up portions being held down by the casing against upward motion, holding said disc 15 down adjacent said sides, the disc at said sides 20 extending substantially across the width of the chamber, said diaphragm bowing up the disc between said held down sides against said second terminal when pressure is sent through said passage. 25

6. A fluid pressure operated switch comprising a casing having a chamber formed therein, the bottom portion of the casing having a passage through it leading into said chamber, a flexible diaphragm in said chamber extending across and sealing said passage, a pair of spaced terminals insulatively mounted in the upper portion of the casing having their inner ends exposed to the interior of the chamber, and a metallic plate 30 spring in the chamber above said diaphragm 40 having one end engaging the first of said terminals, the opposite end of the spring being normally at a distance below the second of said terminals, the opposite sides of the spring intermediate said ends being held down against upward motion by reacting against the casing, said diaphragm bowing up the spring between its held down sides, against the second of said terminals when pressure is sent through said passage. 45
